UNITED STATES PATENT OFFICE.

ARTHUR CUMMING NOAD, OF NEW YORK, N. Y.

GAS-LAMP.

SPECIFICATION forming part of Letters Patent No. 783,887, dated February 28, 1905.

Application filed July 14, 1904. Serial No. 216,537.

To all whom it may concern:

Be it known that I, ARTHUR CUMMING NOAD, a citizen of the United States of America, and a resident of 63 Park Place, New York city, 5 State of New York, at present residing at 12 Buer road, Fulham, in the county of London, England, have invented certain new and useful Improvements in Gas-Lamps, of which the following is a specification.

10 This invention has reference to gas-lamps, particularly incandescence gas-lamps, and has for its object to provide the lamp with a movable screen or similar device which will protect the incandescence mantles from injury by wind or drafts of air, to which they would otherwise be exposed when the globe were moved into a position for permitting the inspection or repair of the mantles, the said screen being nevertheless so constructed that 15 ready access can be had to the said mantles when the screen is in its protective position.

In the accompanying drawings, Figure 1 is a sectional elevation of an incandescence lamp constructed in accordance with my invention, 20 the globe being represented in its raised or ordinary position. Fig. 2 is a sectional elevation with the globe represented in its lowered position—*i. e.*, the position to which it is moved to give access to the mantles. Fig. 3 25 is a detail vertical section. Fig. 4 is a sectional plan view showing a modification.

A is the central gas-supply tube, which also serves as the support for the lamp.

B is the globe.

30 C is the draft-screen.

D D are the burners, and E is the chimney.

The globe is carried by a gallery b, supported by a bush or collar b', which is slidably mounted on a tailpiece a, depending from 40 the lower end of the central support A. Normally the said gallery and the globe it supports are kept in the raised position, Fig. 1, by means of a set-screw b''. The lower end of the tailpiece a has a screw-threaded plug a', 45 which is capable of acting as a stop-piece to prevent the gallery and globe escaping from the tailpiece in the event of the set-screw b'' being accidentally released. To enable the gallery and globe to have sufficient length of 50 downward travel, the tailpiece a has a screw-

threaded aperture in its lower end, to which an extension-piece of rod a'' can be connected. The said extension-piece has its upper end somewhat reduced in diameter, so that when fitted together the tailpiece a and extension-piece a'' constitute a uniformly-thick guide-rod, on which the bush b' can freely slide. At its lower end this rod or extension-piece has a protuberance a'', which supports the gallery and its globe when they are in their 60 lowered position, Fig. 2. I do not confine myself to the above-stated means for enabling the globe to be shifted into its lowered position, as any other suitable means may be employed for this purpose. 65

The draft-screen C is preferably constructed of a tube of sheet metal, although glass or mica might in some cases serve equally well. It is furnished with a hinged or sliding door c, which is arranged in such position that when the globe is lowered and carries the screen C 70 down with it said door can be opened to give convenient access to the mantles. The lower end of the said screen is provided with a ring or band c', to which the globe is detachably 75 connected by means of set-screws c''. This ring or band c' serves to intercept any air-drafts that might find their way into the lower end of the draft-screen when the globe is in its lowered position. The screen is capable of 80 angular motion, so that in the event of there being any wind or local draft the screen can be turned in the desired direction to bring the aforesaid door c into a position remote therefrom, so that said door may then be opened 85 without fear of the mantles being injured by the wind or draft.

The burners D communicate with the central tube A, and the mantles d d are grouped around the said tube, from which they are 90 suspended by arms d' d'.

The chimney E has at its upper end a cap or dome e, which is connected by a screw e' to the tube A, thereby supporting the entire chimney. When the globe is in its raised position, the said draft-screen C lies completely within the said chimney, as represented in 95 Fig. 1.

In order to give additional steadiness to the draft-screen C and guide the same in its move- 100

ment, I may provide its upper part with a spider-frame c^3 , which when said screen assumes its lowered position will rest upon a collar a^4 on the tube A, as shown by Figs. 3 and 4.

5 What I claim, and desire to secure by Letters Patent of the United States, is—

1. In an incandescence gas-lamp, the combination with the chimney, the burner and the globe, of a movable draft-screen for the mantles, means for limiting the extent of movement of said draft-screen, and means for affording access to the mantles when the draft-screen is in its protecting position around the mantles.
- 15 2. In an incandescence gas-lamp, the combination with the chimney, the burner and the globe, of a movable draft-screen for the mantles, means for limiting the extent of movement of said draft-screen, and a closable opening in said draft-screen for affording access to the mantles when the draft-screen is in its protecting position around the mantles.
- 20 3. In an incandescence gas-lamp, the combination with the chimney, the burner, and the globe; of a movable draft-screen for the mantles, means for connecting said draft-screen with the globe so as to move simultaneously therewith, when the latter is raised or lowered, and means for limiting the extent of movement of said draft-screen substantially as described.
- 25 4. In an incandescence gas-lamp, the combination with the chimney, the burner, and the globe; of a movable tubular draft-screen for the mantles, means for connecting said draft-screen with the globe so as to move simultaneously therewith when the latter is raised or lowered, means for limiting the descent of said screen and globe, and means for affording access to the mantles when said screen is in its protective position relatively thereto substantially as described.
- 30 5. In an incandescence gas-lamp, the combination with the chimney, the burner, and the globe; of a tubular draft-screen for the mantles, movable vertically and angularly, means for connecting said draft-screen with the globe so as to move simultaneously therewith when the latter is raised or lowered, means for limiting the descent of said screen and globe, and means on said screen for affording access to the mantles, when said screen is in its protective position relatively to the mantles substantially as described.
- 35 6. In an incandescence gas-lamp, the combination with the chimney, the burner and the globe, of a tubular draft-screen for the mantles adapted to assume a position to protect the mantles from air-drafts simultaneously

with the movement of the globe from its position around the mantles, means for limiting the extent of movement of the draft-screen, and a movable door on said screen for affording access to the mantles when the screen is in its protecting position relatively to the mantles, substantially as described.

65 7. In an incandescence gas-lamp, the combination with the chimney, the burner, and the globe; of a tubular draft-screen for the mantles, movable vertically and angularly, a ring or band located around and connected with the lower end of said screen, means for connecting the globe to said ring or band, means for limiting the descent of the screen and globe, and a sliding door on said screen for affording access to the mantles, when said screen is in its protective position relatively to the mantles substantially as described.

70 8. In an incandescence gas-lamp, the combination with the chimney, the burner, and the globe, of a tubular draft-screen for the mantles, movable vertically and angularly, a ring or band located around and connected with the lower end of the said screen, means for connecting the globe to said ring or band, means for supporting the screen and globe in the raised position, means for limiting the descent of the screen and globe, and a sliding door on said screen for affording access to the mantles, when said screen is in its protective position relatively to the mantles substantially as described.

75 9. In an incandescence gas-lamp, the combination with the chimney, the burner, and the globe, of a tubular draft-screen for the mantles, movable vertically and angularly, a ring or band located around and connected with the lower end of said screen, means for detachably connecting the globe to said ring or band, a detachable stop-piece at the lower end 80 of the lamp-support for retaining the globe and screen in their raised position, an extension guide-rod for attachment to the part occupied by said detached stop-piece, terminating in a protuberance for limiting the descent of said screen and globe, and a sliding door on said screen for affording access to the mantles, when said screen is in its protective position relatively to the mantles substantially as described.

90 In testimony whereof I have hereunto set my hand, in presence of two subscribing witnesses, this 30th day of June, 1904.

ARTHUR CUMMING NOAD.
